UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

FURNACE.

1,248,661.

Specification of Letters Patent. Patented Dec. 4, 1917.

Application filed June 30, 1914. Serial No. 348,139.

To all whom it may concern:

Be it known that I, DAVID S. JACOBUS, a citizen of the United States, residing at Jersey City, in the county of Hudson and State of New Jersey, have invented certain new and useful Improvements in Furnaces, of which the following is a specification.

My invention relates to a furnace construction and more particularly to a gate or back adapted to be placed above the rear of a traveling grate to form a dam or obstruction to the passage of the ash and clinkers after the ash and clinkers have passed beneath a water-cooled partition. In the particular form shown, the gate or back is yielding and comprises a rotatable shaft having detachable pieces secured thereto and placed at the rear of a water cooled partition comprising a water box or water boxes so as to protect the shaft and other parts from the direct and radiant heat of the fire. The detachable pieces secured to the shaft hang therefrom so as to close the opening between the upper run of the grate and the water box, and are adapted to be swung rearwardly by the pressure of the ash and clinkers, as the grate travels rearwardly, to permit the ash and clinkers to fall over the end of the grate to the ash pit.

The invention will be understood by reference to the accompanying drawings in which Figure 1 is a rear elevation broken away, of the yielding back with the walls of the furnace in section; Fig. 2 a side elevation partly in section; Figs. 3 and 4 front and side elevations respectively of one of the links or detachable sections of the yielding back; Fig. 5 an enlarged section through the back, the lower part of the detachable piece being broken away; Fig. 6 a side elevation showing the back swung rearwardly to permit the ash and clinkers to fall to the rear of the grate; and Fig. 7 a transverse section on the plane of the line 7-7 of Fig. 3. Similar reference numerals indicate similar parts in the several views.

Referring to the drawings, the numeral 1 designates the rear of a chain grate stoker which may be of any usual or well-known construction, that shown comprising a series of pivoted links adapted to travel around front and rear sprocket wheels. At the rear of the stoker is a vertical wall 2 from which an arch 3 is sprung. Below the arch and above the rear of the stoker is a water cooled

partition shown as consisting of transverse water boxes 4 and 5 which are connected to the boiler circulation by pipes 6 and 7, respectively, leading to a drum 8. A single water box may be used instead of the two boxes 4 and 5. Side water boxes 9 may be nipped to the box 4.

Rotatably supported in a bearing in one of the side walls, and upon saddles 10, is a shaft 11, shown as made from a heavy steel pipe. Attached to the shaft are detachable or replaceable cast iron pieces having their upper ends 12 curved to embrace the shaft, and lower depending portions 13 which are preferably perforated along the center for ventilation, and have two ribs or fins 14 to conduct away the heat from that part of the pieces which face the fire, and so prevent overheating. The side edges of the portions 13 may have indentations 15 so that when assembled, as shown in Fig. 1, ventilating openings will be provided between the pieces. These pieces are secured to shaft 11 by a special bolt 16 and a nut 17. The head of the bolt is passed through a slot in the shaft, the bolt being so formed that after passing the head through the slot it may be given a quarter turn and drawn forward to a firm bearing. The shaft with the attached pieces constitute a yielding gate or back which is held in position by a weight 18 hung on the end of a lever 19 secured to the shaft. Instead of a weight a spring may be employed to hold the back in normal position.

As shown, the shaft 11 is placed at the rear of the water boxes so as to protect it, and the attached pieces constituting the back, from the direct action and radiant heat of the fire and so prevent burning out of these parts. This avoids the necessity of cooling the shaft by the circulation of water therethrough, or blowing in air with steam jets, or the like. Tests have indicated that placing the back at the rear of a water box or water boxes gives ample protection, and the back so placed has stood up under most severe conditions of service.

The purpose of the yielding back, in the form shown one which swings, as distinguished from one which moves bodily to the rear, is to form a yielding dam or obstruction to the passage of the ash and clinkers after they have passed beneath the water box, and to permit the ash and clinkers to fall to the rear of the grate as the travel.

of the grate carries the ash and clinker to the rear. For this purpose the weight 18 is so adjusted that in case clinker builds up a certain amount in front of the gate it will cause the back or gate to rotate and allow the clinker to fall to the ash pit. This action will be understood by reference to Fig. 6. As the chain grate travels to the left, the ash will pile up against the front of the gate 10 or back and as it accumulates and is forced under the water box it will swing the gate to the left, against the action of weight 18, and allow the ash and clinker to pass over the rear of the grate. The water box is placed at such a height that any ash and 15 clinker will readily pass beneath it. The swinging gate or back may be operated in the following ways:

1. The weight 18 may be so adjusted that 20 the lower edge of the back will be continually moved slightly one way or the other so as to allow the ash and clinker to pass beneath it. When this action is desired the swinging back is set near the rear end of the 25 grate, as shown in Figs. 2 and 6, so that the "breaking" of the stoker links will assist in forcing the ash and clinker beneath the lower edge of the gate. By the "breaking" of the links I mean the projection of the 30 edge of one link above the face of the other, where the links pass over the rear sprocket wheel and the moving apart of the ends of the links at that point.

2. The swinging gate or back may be set 35 so that the lower edge will come at a given height above the grate and will be held immovable except under extraordinary conditions, such as when a brick from the stoker arches falls and jams between it and the 40 grate, in which case it would raise the weight 18. To effect such an adjustment the lever 19 will rest upon an adjustable stop or support 20 (as shown in Fig. 1) and the weight 18 made heavy enough to prevent the swinging gate or back from moving under ordinary 45 operating conditions.

3. The swinging gate may be set at a fixed point using a stop and relieving device, as in the second method of operation 50 above described, and the ash and clinker allowed to build up at the rear of the grate. The gate may then be opened from time to time either by hand or by means of an automatic device arranged to act periodically.

55 In chain grate practice stoker water boxes are employed. As a rule there is one such box corresponding to the one indicated at 4. The height of this box above the chain grate stoker must be varied for different grades of 60 coal. If two grades of coal are burned at the same plant where the height should be different for one coal than it is for the other, there is difficulty through using a back at a given height above the grate. It is a difficult 65 matter to adjust the height of the water

boxes above the grate as they are usually connected to the boiler circulation. In some instances the water boxes are provided with an independent circulation of water, but in such case the heat imparted to the water 70 must usually be wasted, whereas with the box connected to the boiler circulation the heat imparted to the water used for cooling the box is saved. With the boxes connected in the circulation it would be a difficult matter to regulate the height of the box above the stoker, and the yielding or swinging gate or back affords an easy means for regulating the height, and at the same time embodies advantages not secured with a fixed back. 75

What I claim and desire to secure by Letters Patent of the United States is:

1. The combination with a chain grate stoker, of a water partition above the rear portion, and a back in the rear of the water 80 cooled partition extending downwardly below the bottom of the partition to form a deeper obstruction to the passage of material on the grate after it passes beneath the water cooled partition.

2. The combination with a chain grate stoker, of a water partition above the rear portion, and a back in the rear of the water cooled partition extending downwardly below the bottom of the partition to form a 95 deeper obstruction to the passage of material on the grate after it passes beneath the water cooled partition, the water cooled partition being arranged to protect the support for the back from the heat of the fire. 100

3. A chain grate stoker having a pivotally mounted back above its rear portion, and a water cooled partition in front of the pivoted back arranged to protect it from the heat of the fire, the pivoted back extending 105 downwardly below the water cooled partition to form a deeper obstruction for the passage of material on the grate after it passes beneath the water cooled partition.

4. The combination with a chain grate 110 stoker, of a water partition above the rear portion, and a back in the rear of the water cooled partition extending downwardly below the bottom of the partition to form a deeper obstruction to the passage of material 115 on the grate after it passes beneath the water cooled partition, said back consisting of a series of separate replaceable sections.

5. The combination with a chain grate stoker, of a water partition located over its 120 rear portion, a pivotally mounted back in the rear of the water partition and extending down below it, a stop to limit the forward movement of the back, and means for holding the back in the forward position as limited by the stop, said means being arranged to yield under extraordinary pressure. 125

6. The combination with a chain grate stoker, of a swinging back mounted over its rear portion, stop mechanism for limiting 130

the forward swing of the back, and means for normally holding the back in its forward position against the stop, said means being arranged to yield under extraordinary pressure against the back.

7. The combination with a chain grate stoker, of a swinging back mounted over its rear portion, stop mechanism for limiting the forward swing of the back, and means for normally holding the back in its forward position against the stop, said means being arranged to yield under extraordinary pressure against the back, said stop mechanism being adjustable to change the position of the lower edge of the back with respect to the grate.

8. The combination with a chain grate stoker, of a water partition mounted above its rear portion, said partition comprising a plurality of superimposed water boxes with means for circulating water therethrough, and a back mounted in the rear of the water boxes and projecting downwardly below the bottom of the lower water box to form a deeper obstruction to the passage of the material on the grate after it passes beneath the lower water box.

9. The combination with a chain grate stoker, of a water partition mounted above its rear portion and consisting of a plurality of superimposed water boxes, each box being separately connected to the water circulation of the boiler, and a back supported in the rear of the water boxes and projecting downwardly below the bottom of the lower water box to form a deeper obstruction to the passage of the material on the grate.

10. The combination with a chain grate stoker, of a swinging shaft having a series of separate, depending, replaceable sections rigidly secured thereto, said sections constituting a back to obstruct the passage of material on the grate, and means for yieldingly holding the shaft in position so that the back will obstruct the passage of the material.

In testimony whereof I have hereunto signed my name in the presence of two subscribing witnesses.

DAVID S. JACOBUS.
